EX

OR D 13,466

No. 13,466

DEC 5, 1882

UNITED STATES PATENT OFFICE.

JAMES H. FLYNN AND JACOB A. SNELL, OF SCHENECTADY, NEW YORK.

DESIGN FOR A WHISK-BROOM CASE.

SPECIFICATION forming part of Design No. 13,466, dated December 5, 1882.

Application filed October 24, 1882. Term of patent 7 years.

To all whom it may concern:

Be it known that we, JAMES H. FLYNN and JACOB ARTHUR SNELL, citizens of the United States, residing at Schenectady, in the county of Schenectady and State of New York, have invented and produced a new and original Design for Whisk-Broom Cases, of which the following is a specification, reference being had to the accompanying illustration, forming part thereof.

10 A is the whisk-broom case, tapered and having the general form of the brush, and open at the top and bottom. Bands *a a* are placed on the case at the top and bottom parallel to the edge; but these bands may be omitted. Between the bands on the body of the case may be placed one or more ornaments, *b*.

15 B is the back of the whisk-broom case, made in the general form of a horseshoe.

20 The case A is attached to the horseshoe-shaped back B, and preferably in such a way that it lies between the sides of the shoe and between the toe and heels, so that the whole of the shoe is visible outside of the case. The

25 back B may be provided with studded ornaments *c*. The case A and horseshoe-shaped back B are also arranged in such relation to each other that when the whisk-broom is placed in the case the shoulders of the whisk-broom

30 *D* are held between the heels of the shoe, as shown.

We claim—

1. The design for a whisk-broom case herein shown, consisting in the case A, having bands *a a*; and horseshoe-shaped back B.

2. The design for a whisk-broom case, which consists in the case A, having ornament *b*, and horseshoe-shaped back B.

3. The design for a whisk-broom case, which consists in the case A, having bands *a a* and ornament *b*, and the horseshoe-shaped back B.

4. The design for a whisk-broom case, which consists in the case A and horseshoe-shaped back B, having studded ornaments *c*.

5. The design for a whisk-broom case, which consists in the case A and back B, arranged so that when the whisk-broom is placed in the case its shoulders lie between the heels of the horseshoe-shaped back.

6. The design for a whisk-broom case, which consists in a case, A, placed on a representation of a horseshoe, forming the back B of the case, as shown.

7. The design for a whisk-broom case herein described and shown, the same consisting of a horseshoe-shaped back, B, and case A.

JAMES H. FLYNN.
JACOB ARTHUR SNELL.
